UNITED STATES PATENT OFFICE.

ALBERT NEAL, OF KOKOMO, INDIANA.

LIFTING-JACK.

1,385,489.

Specification of Letters Patent. Patented July 26, 1921.

Application filed June 14, 1920. Serial No. 388,764.

To all whom it may concern:

Be it known that I, ALBERT NEAL, a citizen of the United States, residing at Kokomo, in the county of Howard and State of Indiana, have invented certain new and useful Improvements in Lifting-Jacks, of which the following is a specification.

This invention relates to that class of lifting jacks shown in my pending applications Nos. 256,496 and 286,021; and the principal object of the present invention is to provide a lifting jack which is not restricted to the accomplishment of the limited objects sought in my prior applications, but is directed to a more ingenious organization of parts whereby all the objects which are attained in my previous applications can be attained in the present structure.

I accomplish the above objects, and such others as may appear from a perusal of the following description and claims, by means of the construction illustrated in the accompanying drawings, forming a part hereof, in which—

Figure 1 illustrates a side elevation of my improved lifting jack, showing the parts in their initial position for elevating the lifting-bar. Fig. 2 illustrates the position of the parts at the end of their initial movement in elevating the lifting-bar. Fig. 3 illustrates the initial position of the parts in lowering the lifting-bar. Fig. 4 illustrates the position of the parts at the end of their initial movement in lowering the lifting-bar. Fig. 5 illustrates the position of the parts assume in dropping the lifting-bar at one operation. Fig. 6 is an edge view, on the line 6—6 in Fig. 4. Fig. 7 is a vertical sectional view, on the line 7—7 in Fig. 5. Fig. 8 is a cross section, on the line 8—8 in Figs. 4 and 6. Fig. 9 is a view partly in section and partly in elevation, on the horizontal plane 9—9 in Fig. 6.

Referring to the drawings, 15 represents the standard or frame having a base 16, and said frame is also provided with a longitudinal channel 17 which is adapted to receive and form a guide for a movable lifting-bar 18, the latter being provided in one edge with teeth 19. Channel 17 is formed by the raised end walls 20 and 21 of frame 15, and wall 21 is of less height than wall 20 so as to provide working clearance to permit the engagement of the pawls with the actuator

bar 18. Housing 15 is further provided with a laterally disposed integral enlargement 22 for the mounting of the pawls and the actuator-lever.

As the present jack is rather short of length, to permit it to be carried in an ordinary automobile tool-box, it is desirable to maintain the greatest possible efficient range of extension without unduly straining the parts. This is accomplished by partly incasing lifting bar 18 in a channel shaped movable guide-bar 23 (see Fig. 8) one flange of which rests against the exposed face of lifting-bar 18 and the remaining flange 25 riding against the external face of housing 15. Guide-bar 23 is induced to travel in unison with lifting-bar 18 through the medium of an integral transverse rib 26, on bar 18, engaging an overhanging lip 27 forming a part of guide-bar 23, as clearly shown in Fig. 3. To equalize the strain on both sides of lifting-bar 18 the latter is provided on its edge opposite the edge carrying the transverse rib 26 with a similar rib 28 which contacts the under edge of a loop 29 formed integrally with the guide-bar 23 and which passes across the exposed face of lifting bar 18. By means of the channel formation of the guide-bar 23, which permits it to extend across the exposed face of lifting-bar 18 and a part of the external face of frame 15, a part of frame 15 is within the embrace of the channel guide-bar 23, whereby the guide-bar 23 overlaps frame 15 and lifting-bar 18 and not only serves to maintain the parts in alinement when the lifting-bar 18 is extended, but prevents lateral displacement of the lifting-bar from the frame 15 without the use of ribs and grooves, as appear in my earlier applications, and which are not only difficult to cast but increase the cost of manufacture.

Lifting-bar 18 may be extended or retracted according to the desire of the operator, by means of a load supporting pawl 30 and a bar actuating pawl 31 which are alternately oscillated in opposite directions through the location of their points of attachment relatively to pivot 32 of the actuator-lever 33. Pivot 32 comprises a trunnion formed integrally with actuator-lever 33, and this trunnion passes through the adjacent wall of enlargement 22 of housing 15 and is threaded on its free end to receive a

nut 33^a so that displacement of lever 33 is prevented. With the pawls occupying the positions indicated in Fig. 1 it will be seen that pawl 30 is engaged with lifting-bar 18 and is supporting the load, whereas the free end of pawl 31 is disengaged from said teeth. When the actuator lever 33 is elevated toward the position indicated in Fig. 2 the first movement of angular travel of said lever is translated to the pawls to cause pawl 31 to engage the tooth immediately above the tooth engaged by load supporting pawl 30, and during the continued upward travel of lever 33 pawl 31 is caused to move upwardly and carry lifting-bar 18 with it. During the above movement of pawl 31 and bar 18 the load is removed from pawl 30 and the latter moves downwardly and reengages one of the teeth from lower down in bar 18 by the time bar 33 reaches the limit of its upward travel, when pawls 30 and 31 will be occupying the positions indicated in Fig. 2. The upward movement of lever 33 is arrested by the engagement of the edge 34 of the aperture in the oval shaped ring 35, which is a part of lever 33, coming into contact with a fixed post 36 which is mounted on the adjacent face of enlargement 22 of frame 15. During the upward movement of bar 33 the weight of cam 40 is sustained by pawl 31 and serves to hold and prevent disengagement of the free end of pawl 31 from bar 18. Cam 40 varies the movements of the pawls, depending upon the position the cam occupies on its pivot, and is one of the predominating elements in the present device, as the following description discloses. Thus, in examining Fig. 1, it will be observed that the weighted portion 41 of cam 40 is on the side of its pivot 43 to cause the cam to rest heavily upon a pin 44 carried by pawl 30 and thereby prevent, at this time, the accidental displacement of said pawl from teeth 19. When, however, lever 33 is being elevated into the position indicated in Fig. 2, the weight of cam 40 is removed from pawl 30 and is shifted to pin 45 of pawl 31, so that pawl 30 is free to disengage itself from teeth 19 and move downwardly along lifting-bar 18 as the upward movement of lever 33 continues.

The heretofore described movements of the parts impart a movement for a progressive extension of lifting-bar 18, and while cam 40 occupies the position indicated in Figs. 1 and 2 lifting-bar 18 cannot be retracted as cam 40 must be moved on its pivot to assume the position indicated in Fig. 4 to permit the progressive lowering of lifting-bar 18. The reason for this is that when the position of cam 40 is shifted on its pivot its irregularly shaped surfaces will assume new angles and thereby change the action of pawls 30 and 31. The movement of cam 40 on its pivot from the position indicated in

Fig. 1 to that indicated in Fig. 3 is determined by means of the fixed post 36 coming into contact with the inner edge 42 of the irregularly shaped aperture in cam 40, as clearly indicated in Fig. 4.

When it is desired to progressively lower lifting-bar 18, the first portion of the upward movement of lever 33, in view of point of connection between pawl 31 and lever 33 relatively to pivot 32 of said lever 33, would normally move the free end of pawl 31 into engagement with the notch in bar 18 lying immediately in advance of said pawl (Fig. 1) but the action of cam 40 at this time prevents the free end of said pawl from entering that particular notch, for the reason that pawl 31 should engage lifting-bar 18 higher up to effect the lowering of the latter. With the first upward movement of lever 33 the position of weighted portion 41 of cam 40 moves the cam backwardly from bar 18 and through the contact of edge 42 of the irregularly shaped aperture in cam 40 with pin 45 of pawl 31, a corresponding movement is imparted to the free end of pawl 31, or from the position indicated by full lines to the position indicated by dotted lines in Fig. 4. As the upward movement of lever 33 continues the convex-shaped extension 50 of cam 40 is brought into contact with the underside of pin 44 on the now downwardly moving pawl 30, which arrests further oscillatory movement of cam 40 on its pivot. The weight of cam now being shifted from pawl 31 to pawl 30, through the breaking of the contact between edge 42 and pin 45 pawl 31 is released and is free to move upwardly and enters a notch higher up in bar 18 by the time lever 33 reaches the limits of its upward travel. The release of pawl 31 however has been delayed long enough and the pawl has moved upwardly far enough above its former position to enable its free end to enter a notch higher up in bar 18 than it would have engaged if its movement previously had not been restrained by cam 40. During the latter part of the upward movement of lever 33 producing the above results the convex-shaped surface of extension 50 has moved sufficiently forward to permit pin 44 to drop into a recess 51 and causing the withdrawal of the free end of pawl 30 from teeth 19, leaving the pawls in the positions indicated in Fig. 2, when lever 33 reaches the limits of its upward travel. Pawl 30 is now held by the hook formed by the recess 51 in extension 50 engaging pin 44. In this position with the first downward movement of lever 33 the free end of pawl 30 is moved away from bar 18 until its outer face contacts the adjacent face of the now downwardly moving pawl 31 whereby the weight of cam 40 is removed from pawl 30 and effects the disengagement of pin 44 from recess 51 and directs the free end of pawl 30

back into engagement with teeth 19 under the continued downward movement of lever 33, and when lever 33 reaches the limits of its downward travel the pawls will occupy the 5 positions indicated in Fig. 4. This last described movement is repeated each time lever 33 is lowered, with cam 40 occupying the position indicated in Fig. 4.

The description so far relates to the movements of progressively elevating and lowering lifting-bar 18, and the manner in which 10 the bar when elevated may be dropped at a single operation, and which is desirable in many cases, will now be described.

15 When the present jack is employed for raising an automobile to enable a tire to be changed there is no necessity for a progressive lowering movement of the load, for the reason that an inflated pneumatic tire acts 20 as a cushion in absorbing shocks and thereby reduces the liability of injury to the motor car. When lifting-bar 18 is in an extended position and it is desired to drop the bar at one operation, the operator moves 25 cam 40 approximately midway of its range of oscillatory travel (see the comparative position of cam 40 in Fig. 5 relatively to the positions shown in Figs. 1 and 4) whereby the restraint of cam 40 is entirely removed 30 from pawl 31 which allows the latter to be disengaged from teeth 19 through the lowering movement of lever 33, and when said lever moves a sufficient distance the inner edge 42 of the aperture in the oval 35 shaped ring 35 will engage and actuate pin 44 to disengage pawl 30 from teeth 19, thus leaving the lifting-bar 18 unsupported and free to drop.

Having thus fully described my said in-

vention, what I desire to secure by Letters 40 Patent, is—

1. In a lifting jack, a channeled standard, a toothed lifting-bar moving in the channel of said standard, and a movable guide-bar having independent movement of the standard and adapted to extend across the edge 45 and one side of the standard and the exposed side of the lifting-bar for maintaining the alinement of the associated parts.

2. In a lifting jack, a channeled standard, 50 a toothed lifting-bar moving in the channel of said standard, a movable guide-bar having independent movement of the standard and adapted to embrace the lifting-bar and standard for maintaining the alinement 55 of the associated parts, means for preventing independent movement between the guide-bar and the lifting-bar, and means for actuating the two bars longitudinally of the standard.

3. In a lifting jack, a channeled standard, a toothed lifting-bar moving in the channel in said standard, a guide-bar adapted to embrace the lifting-bar and standard for maintaining the alinement of the associated 65 parts, a bar sustaining pawl and a bar actuator pawl, a lever for mounting and for alternately actuating said pawls for the progressive extension of the bar, and a cam carried by the lever and having independent 70 movement of the lever for effecting the complete disengagement of both pawls from the lifting-bar.

In witness whereof I have hereunto set my hand and seal at Indianapolis, Indiana, 75 this 9th day of June, A. D. one thousand nine hundred and twenty.

ALBERT NEAL. [L. S.]
